UNITED STATES PATENT OFFICE

172,543

EARRING OR THE LIKE

Louis Kramer, New York, N. Y., assignor to Kramer Jewelry Creations, Inc., New York, N. Y.

Application March 4, 1954, Serial No. 29,337

Term of patent 3½ years

(Cl. D45—9)

To all whom it may concern:

Be it known that I, Louis Kramer, a citizen of the United States of America, residing in New York city, county of New York, and State of New York, have invented a new, original, and ornamental Design for an Earring or the like, of which the following is a specification, reference being had to the accompanying drawing, forming part thereof.

Fig. 1 is a plan view of an earring or the like showing my new design.

Fig. 2 is an edge view thereof.

I claim:

The ornamental design for an earring or the like, substantially as shown.
